(57) **CLAIM**

The ornamental design for a ceiling fan housing, as shown and described.

DESCRIPTION

FIG. 1 is a perspective view of the ceiling fan housing showing my new design;

FIG. 2 is a front elevational view thereof;

FIG. 3 is a rear elevational view thereof;

FIG. 4 is a bottom plan view thereof; and,

FIG. 5 is a top plan view thereof.

Any solid black area in the drawings represents an opening formed in the ceiling fan housing.

Any broken line illustration of environmental structure in the drawings is not part of the design sought to be patented.
